UNITED STATES PATENT OFFICE.

WILLIAM C. RATHJEN, OF ST. LOUIS, MISSOURI.

CHILD'S FOLDABLE TOILET-CHAIR.

1,391,791.

Specification of Letters Patent. Patented Sept. 27, 1921.

Application filed October 3, 1919. Serial No. 328,212.

To all whom it may concern:

Be it known that I, WILLIAM C. RATHJEN, a citizen of the United States, residing at the city of St. Louis, in the State of Missouri, have invented certain new and useful Improvements in Children's Foldable Toilet-Chairs, of which the following is a specification.

This invention comprises improvements 10 in the construction of foldable chairs to be used by children for toilet purposes. The construction is adaptable for use, also, for other purposes.

The chair is capable of being so folded 15 that it can be carried in a suitcase or a small package.

Simplicity and cheapness of construction, compactness when folded, and rigidity when unfolded are some of the advantages of this 20 device.

In the accompanying drawings forming part of this specification, in which like numbers of reference denote like parts wherever they occur,

25 Figure 1 is a top plan view with the lid up;

Fig. 2 is a front elevation;

Fig. 3 is a side elevation;

Fig. 4 is a top elevation with the lid down 30 and the device as a whole folded;

Fig. 5 is a top plan view, showing the device folded, but with the lid up; and

Fig. 6 is a sectional view on the line 6—6 in Fig. 4.

35 Figs. 1, 2, and 3 of the drawings show the chair unfolded and ready for use. Figs. 4, 5, and 6 of the drawings show the device folded and ready for packing away or transportation.

40 The legs 1 are pivoted by pins 2 to front and rear members 3 and 4, and seat, when unfolded, in notches 5 in the seat 6, having the opening 7. The flange-like members 3 and 4 are attached to and depend from the 45 seat 6.

The step 8 is fastened to the seat 6, and extends slightly to the rear of the same, so as to overlap rear member 4, the rearward notches 5 passing through the step 8 as well 50 as the seat 6.

Hinges 9 fasten lid 16 to step 8.

Hooks 11, by means of eyelets 12, attach the lid 10 to the side arms 13, when the chair is in unfolded position, thus adding to its 55 stability or rigidity. Hooks 14 are borne by the ends of a piece of tape 10 or strap

or the like. The said hooks 14 are hooked in the eyelets 15 attached to side arms 13. The purpose of the strap or tape 10 or the like when hooked in place, as just stated, is 60 to hold the child in the chair. Children using such a chair are usually quite young and need to be supported from falling out by some such means.

The legs 1 are braced by tie-rod 17, which 65 imparts solidity to the structure, especially from front to back. So long as the legs 1 stay in notches 5, the structure is rigid transversely also, but to prevent accidental displacement of the legs 1 from the notches 5, 70 hooks 11 and eyelets 12 are provided.

To fold the chair, hooks 11 are unhooked from eyelets 12. The arms 13 are then grasped in the hands, the lid 10 falling of itself, swinging on the hinges 9. A slight 75 outward pull may then be given to arms 13, so as to free legs 1 from binding on the corners 18. This outward movement is not absolutely essential, but, if desired, is permitted by the grooves 19 being made to extend far enough toward the ends of front and rear members 3 and 4 to permit of it. The pins 2 fit in grooves 19 and slide therein while the chair is being either folded or unfolded—in opposite directions, according 80 to which of these operations is being performed. The grooves 19 extend toward the middle of the length of front and rear members 3 and 4, the said grooves extending far enough toward the said center to enable the 85 legs, when folded, neatly to underlie the seat 6.

The chair as a whole is preferably formed in the shape of a square, or in approximately that shape, the width of the seat and length 95 of the front and rear pieces 3 and 4 being substantially identical with the length of the legs plus the thickness of arms 13. Thus, when folded, a very neat and compact package is formed. The feet of legs 1, when 100 folded, contact with the inner or underneath side of arms 13, and as one pair of legs is pushed in from one side and the other pair from the opposite side, the arms 13 limit the movement of the opposing pair of legs, and 105 both pairs of legs and the arms 13 are made to lie neatly within pieces 3 and 4 and underneath seat 6.

It will be observed that there are two grooves 19 in member 3 and two grooves 19 110 in member 4, the same extending in opposite directions from approximately the ends of

- the said members 3 and 4, and the innermost point of the said grooves 19 being respectively past the center of the length of members 3 and 4, thus allowing pins 2 to travel 5 as far inwardly as is necessary to permit the legs 1, arms 13, and tie-rods 17, when folded, completely to underlie seat 6, one of the said leg members, when thus folded, underlying the other.
- 10 The lid 10 is notched at 20, so that when erect the notched part will underlie arms 13 and assist in steadyng the structure.
- Having thus described this invention, I hereby reserve the benefit of all changes in 15 form, arrangement, order, or use of parts, as it is evident that many minor changes may be made therein without departing from the spirit of this invention or the scope of the following claims.
- 20 I claim:
1. In a folding chair of the character described, a seat provided with notches on its opposite sides having depending flanges on two opposite sides thereof, a pair of side 25 members having supporting legs to be received in said notches when the chair is unfolded, said flanges on the seat having superposed grooves therein extending inwardly from a point adjacent the notches in the 30 chair to a central point where they overlap, each of said side members having a pivoted slidable connection in one of said grooves in each of said flanges, whereby said side members and legs may be moved to underlie 35 the seat in superposed relation to each other.
  2. In a folding chair of the character de-

scribed, a seat provided with notches on its opposite sides having depending flanges on two opposite sides thereof and notches in the side edges thereof, a pair of side members having supporting legs to be received in said notches when the chair is unfolded, 40 said flanges on the seat having superposed grooves therein, each of said side members having a pivoted slidable connection in one 45 of said grooves in each of said flanges, whereby said side members and legs may be moved to underlie the seat in superposed relation to each other.

3. In a folding chair, the combination of 50 a seat member having notches in the side edges thereof, there being a pair of flange-like members depending from the said seat, a pair of side members comprising arms and legs, the said legs being received in the 55 said notches and pivoted in relation to the said seat, said legs extending farther below the seat than the arms extend above the seat and the said pivotal points being approximately where the legs and the arms begin, 60 the pivots of each side member being slidably mounted in grooves in the said flange-like members, said grooves being arranged one over the other and extending inwardly 65 from said notches to a point where they overlap, whereby the side members may be folded to underlie the seat within its confines and in superposed relation.

In testimony whereof I hereunto affix my signature.

WILLIAM C. RATHJEN.
